[57] CLAIM

The ornamental design for a menstrual tampon, as shown and described.

DESCRIPTION

FIG. 1 is a perspective view of a menstrual tampon showing our new design;

FIG. 2 is a bottom plan view thereof; and

FIG. 3 is a top plan view thereof.

The side opposite the side shown in FIG. 1 is the same as the side shown in FIG. 1 except that it is traversed from top to bottom by a single straight run of the double cord shown in FIG. 1.
